UNITED STATES PATENT OFFICE.

JOHN PEARSON, OF PULLMAN, ILLINOIS, ASSIGNOR TO THE PULLMAN COMPANY, OF CHICAGO, ILLINOIS, A CORPORATION OF ILLINOIS.

COLLAPSIBLE RACK.

Application filed May 9, 1924. Serial No. 712,042.

The invention has to do with the accommodations provided in the upper berths of standard sleeping cars for the reception of luggage, clothing, and other kindred articles.

5 The accommodations heretofore provided have been the familiar net hammocks, but such hammocks, while adequate in the lower berths where shelf space for the necessarily accessible luggage is provided by the inverted head rests, are not adequate in the 10 upper berths where no shelf space is available for such luggage and the same can only be placed upon the bed to the inconvenience of the occupant.

15 Although such inadequacy has been for years the subject of consideration on the part of those versed in all matters pertaining to the construction of sleeping cars, the hammocks have been considered to be the only 20 feasible equipment for the purpose, owing to the fact that the space between the side of the car and the panel of the berth is completely filled with bedding, head boards and other material when the panel is folded up, 25 and any accommodations provided must consequently be a structure which will not interfere with such use of the space.

The principal object of the invention is to 30 provide a collapsible rack for the upper berths of sleeping cars, which, when in use, furnishes a spacious shelf on which clothing may be laid out and luggage may be placed, and which, when not in use, may be collapsed out of the way against the side of the car.

35 Another object is to provide a rack of the character described which is constructed of flexible material, and is accordingly not subject to breakage or permanent deformation when compactly stored with the other berth 40 materials.

Another object is to provide a rack of the character described which is possessed of the stability of a rigid structure, but is sufficiently yielding to obviate any danger of 45 injury to the berth occupant in case of accidental collision therewith.

Other objects and advantages will occur to those skilled in the art upon a full comprehension of the structural features of the 50 rack.

In order that the invention may be read-

ily understood, an exemplifying embodiment of the same is set forth in the accompanying drawings and in the following detailed description based thereon. As the invention is obviously susceptible of embodiment in other and varied constructural forms without departure from the essence of the invention and without sacrifice of its material advantages, it is to be understood that the drawings and description are to be considered in an illustrative and not in an unnecessarily limiting sense.

In the drawings—

Fig. 1 is an abridged side view of the 65 rack, showing the disposition of the same within the upper berth of a sleeping car;

Fig. 2 is a transverse section through the 70 rack, showing again the disposition of the same;

Fig. 3 is an abridge top view of the rack, showing again the disposition of the same; and

Fig. 4 is a complete top view of the rack.

The rack is preferably composed of several longitudinally extending strips 10, several transversely extending strips 11 which connect with intermediate portions of the strips 10 at intervals throughout the length of the rack, two cables 12 which connect 80 with the ends of the strips 10 and 11 and constitute the marginal portions of the rack, four attaching hooks 13 which connect with the cable 12 at the corners of the rack, two fixtures 14 for supporting the rear corners of 85 the rack, and two fixtures 15 for supporting the front corners of the rack.

The strips 10 and 11 and the cables 12 are formed of flexible materials, and the body portion of the rack is accordingly flexible. 90 A preferred arrangement of these elements is herein disclosed, but it will be understood that any arrangement producing a suitable body portion may be used.

When the rack is mounted in an upper 95 berth 16, the fixtures 14 may be secured to the upper curved side wall 17 of the car at about the desired level of the rack and the fixtures 15 may be secured to the permanent section partitions 18.

The fixtures 14 are ordinary eye brackets in which the rear hooks 13 engage, but the

front fixtures 15 are elongated brackets having downwardly and forwardly diverging rod portions 19 about which the front hooks 13 slidably engage. The upper ends of the fixtures 15 are located above the fixtures 14 adjacent the wall 17, and the lower ends of the same are located in front of the fixtures 14 at about the level of the same.

The rack is collapsed by sliding the front hooks 13 rearwardly and upwardly along the converging rod portions 19 of the fixtures 15, and, when the front hooks 13 have reached the rear end of their travel, the rack will be supported loosely in a collapsed position and will conform yieldingly to the contour of any objects stored in the folded berth. The rack is opened by sliding the front hooks 13 downwardly and forwardly along the rod portions 19 of the fixtures 15, and, when the hooks 13 have reached the front end of their travel, the rack will be held tautly in a substantially horizontal outspread position, owing to the divergent relation of the rod portions 19.

The hooks 13 at one end of the rack may advantageously be provided with turn buckles 20 which may be adjusted from time to time to compensate for any stretching in the body of the rack.

While the rack is particularly adapted for use in the upper berths of sleeping cars, it will be appreciated that the same may also be advantageously used in other confined spaces.

I claim:

1. A collapsible rack of generally rectangular form, and stationary fixtures for supporting the rack at the four corners of the same, the association between the rack and the fixtures being such that the same fixtures are used both for supporting the rack in an outspread position and in a collapsed position.

2. A collapsible rack of flexible material, supporting fixtures adjacent the ends of the rack, a stationary connection between one side of each end of the rack and the adjacent fixture, and a movable connection between the other side of each end of the rack and the adjacent fixture, whereby when the movable connection is moved away from the stationary connection the rack is supported tautly in an outspread position and when the movable connection is moved toward the stationary connection the rack is supported loosely in a collapsed position.

3. A collapsible rack, two fixtures to which two corresponding corners of the rack are connected, and two other fixtures to which the two other corresponding corners of the rack are connected, said last mentioned fixtures having elongated connecting portions which diverge from each other as they approach the level of the first mentioned fixtures, whereby to hold the rack

tautly when the same is outspread in an approximately level position.

4. A collapsible rack, two fixtures to which two corresponding corners of the rack are connected, and two other fixtures to which the two other corresponding corners of the rack are connected, said last mentioned fixtures having elongated connected portions which converge toward each other as they approach the first mentioned fixtures, whereby to hold the rack loosely when the same is in a collapsed position.

5. A collapsible rack including longitudinally extending flexible strips, transversely extending flexible strips connecting intermediate portions of the first mentioned strips, flexible marginal members connected to the ends of both the longitudinally and transversely extending strips, and coupling devices carried by the marginal members adjacent the ends of the rack for attachment to suitable supporting means.

6. A collapsible rack of generally rectangular form including several longitudinally extending flexible strips, several transversely extending flexible strips connecting intermediate portions of the first mentioned strips, two flexible cables connected to the ends of both the longitudinally and transversely extending strips, and four coupling hooks slidably carried by the cables adjacent the corners of the rack for attachment to suitable supporting means.

7. A collapsible rack of flexible material for use in a confined space, two fixed rear brackets for supporting the rear corners of the rack, and two fixed front brackets having downwardly and forwardly diverging rod portions for slidably supporting the front corners of the rack, whereby when the front corners are moved downwardly and forwardly the rack will be held tautly in an outspread position and when the front corners are moved upwardly and rearwardly the rack will be held loosely in a collapsed position.

8. A collapsible rack of flexible material for use in a confined space, adjustable coupling devices at the corners of the rack, two fixed brackets for supporting the rear coupling devices, and two other fixed brackets having downwardly and laterally diverging rod portions for slidably supporting the front coupling devices, whereby when the front coupling devices are slid forwardly the rack will be held tautly in an outspread position and when the front coupling devices are slid rearwardly the rack will be held loosely in a collapsed condition.

9. Fixtures for supporting corresponding corners of a collapsible rack both when outspread and when collapsed, comprising two fixed brackets adapted for attachment to opposing walls, said brackets having inclined rod portions on which the coupling

portions of the rack are adapted to slide when the rack is being outspread or collapsed.

10. Fixtures for supporting corresponding corners of a collapsible rack both when outspread tautly and when collapsed loosely, comprising two fixed brackets adapted for attachment to opposing walls, said brackets

having downwardly and laterally diverging rod portions down which the coupling portions of the rack are adapted to slide when the rack is being outspread. 10

In testimony whereof I have hereunto subscribed my name.

JOHN PEARSON.
